UNITED STATES PATENT OFFICE

106,744

DESIGN FOR A SPECTACLE FRONT

Vincent Tanasso, Harrison, N. Y., assignor to
T. & P. Optical Mfg. Co. Inc., New York, N. Y.,
a corporation of New York

Application July 16, 1937, Serial No. 70,482

Term of patent 14 years

To all whom it may concern:

Be it known that I, Vincent Tanasso, a citizen of the United States, residing in Harrison, county of Westchester, and State of New York, have invented a new, original, and ornamental Design for a Spectacle Front, of which the following is a specification, reference being had to the accompanying drawing, forming part thereof.

In the drawing:

Figure 1 is a front elevation of a spectacle front showing my new design.

Figure 2 is a rear elevation thereof, and
Figure 3 is a top plan view.

I claim:

The ornamental design for a spectacle front, as shown.

VINCENT TANASSO.
